UNITED STATES PATENT OFFICE

EDWARD C. LORENTZEN, OF SCRANTON, IOWA

FEEDING TROUGH AND METHOD OF MAKING SAME

Application filed January 10, 1928. Serial No. 245,699.

This invention relates to feeding troughs for poultry and the like.

The object of my invention is to provide a feeding trough of light material, such as 5 wood, which is softer than the metal troughs which are in common use.

I have found in actual use that the metal troughs are objectionable due to the fact that the fowls peck the side of the trough when 10 gathering food, which results in their bills becoming sore and irritated to such an extent that they will not feed properly. I find that wood is about the best material for this purpose. I am aware of the fact that wood feed- 15 ing troughs have been in common use for a good many years, but they are usually constructed of two pieces, the edge of one being nailed adjacent to the edge of the other, which results in a leaky trough in a short 20 time, as the wood swells and contracts.

It is a further object of my invention to form the two side members of the trough integral.

A further object is to provide improved end 25 members for the side portions which may be cheaply constructed, and yet will bind the said edge and side members together to prevent leaking.

A further object is to provide an improved 30 method of forming the side and end members for said trough.

My invention consists in the construction, arrangement and combination of the various 35 parts of the device, whereby the objects contemplated are attained, as hereinafter more fully set forth, pointed out in my claims, and illustrated in the accompanying drawings, in which:

Figure 1 is a perspective view of segmental 40 portions of the stock from which my improved trough is formed.

Figure 2 is a segmental perspective view of the trough, before the reinforcing end members are applied.

Figure 3 is a perspective view of the reinforcing end members.

Figure 4 is a perspective view of one end of the trough as completed.

My improved trough comprises side mem- 50 bers 10 and end members 11. The body of

the trough is formed substantially V-shaped in cross section, the sides being mounted at an angle relative to each other of less than 90°, preferably 75° or 80°. Troughs having body portions constructed of two side members nailed together have their sides at 90° relative to each other. I find this angle is too great due to the fact that the fowls waste a large amount of the food as the inside faces of the body portion are not steep enough to prevent the food from falling out. I also find that by providing the angle of the walls less than 90°, the objection, of the fowls' bills becoming irritated, is considerably overcome, due to the fact that they strike the sides of the trough with a slanting blow rather than a direct blow, as is the case when the trough is formed on an angle of 90°.

The end members 11 are formed triangular and of a thickness about equal to the thickness of the walls of the body portion, said end members being secured in position by means of suitable nails or screws 12. After the members 11 have been secured in position, I have provided a triangularly shaped sheet metal body portion 13 which is of the same size as the end of the trough, including the ends of the side members. Each edge of the body portion 13 is provided with inwardly extending flange portions 14 and 15. 70 The body portion 13 is placed in position 75 against the outer end of the end member 11 with the flanges 14 adjacent to the outer faces of the body portion 10, while the member 15 is mounted on the upper edge of the member 11. Nails or other suitable fastening devices 16 are used for securing the said flanges to the end members of said body portions. The members 15 and 14 are designed to fit snugly. 80

By this arrangement it will be seen that the sides 10 are rigidly held against the beveled edges of the members 11, so that the joint between the said beveled edges of the member 11 and the side of the trough are formed water tight.

These troughs are particularly designed to be used in feeding crates, such as used by poultry feeders, and must necessarily be of cheap construction. To cheapen the construction of the trough as much as possible, I 95 100

have used the following method of construction, which consists in first providing a rectangular piece of timber of a length equal to the length of the side members of the trough, and of a width equal to the distance between the upper edges of the side members, and may be of any convenient height. The body portions are then formed by setting the timber at an angle relative to a saw, the sides of the timber being at an angle of about 40°. A longitudinal cut is then made which extends to a point midway between the sides of the timber. The timber is then turned end for end, and a second cut is made which will remove a piece of timber designated by the numeral 17 having the shape of a three sided prism. The timber may then be elevated and a second cut made, leaving the desired thickness of the trough between the first two cuts. The timber is then reversed end for end and a second cut made with the result that a V-shaped trough member is removed, the sides of which are formed integral. This operation may be continued until the entire timber has been cut up into troughs.

The body portions are then stacked in piles in the same relation to each other as they were when removed from the timber. These piles are allowed to cure, which greatly assists in preventing the side members from warping, as the side members of one trough will hold the side members of the adjacent trough in place.

To form the end members 11, I take the member 17 and cut it into a series of transversely arranged blocks, in the manner indicated by the transverse lines 18. It will be seen that the beveled edges of the blocks are exactly the same angle as the trough. By this means the end members are quickly, accurately and cheaply formed. After the side members have cured, the end members 11 are applied and the trough is constructed in the manner before stated.

Thus it will be seen I have provided a feeding trough of simple, durable and inexpensive construction.

It will further be seen that I have provided an improved method of forming the body portion of the trough which results in an article which can be easily and quickly assembled and which is rigid and tight.

I claim as my invention:

1. The method of forming a feeding trough having a V-shaped body portion and triangularly shaped end members, which consists in first forming a timber rectangular in cross section of a width equal to the width of the trough and of a length equal to the length of the trough, then cutting the timber longitudinally into V-shaped trough members, then removing the prism shaped member which results therefrom, then cutting said prism shaped member transversely to form

triangularly shaped end members, stacking the trough members to season, and then securing the end members into position.

2. The method of forming a feeding trough having a V-shaped body portion and triangularly shaped end members, which consists in first forming a timber rectangular in cross section of a width equal to the width of the trough and of a length equal to the length of the trough, then cutting the timber longitudinally into V-shaped trough members, then cutting a prism shaped member transversely to form triangularly shaped end members, stacking the trough members to season, and in overlapping relation to each other in the same manner as cut from the timbers, and then securing the end members into position.

3. The method of forming a feeding trough having V-shaped body portion and triangularly shaped end members, which consists in first forming a timber rectangular in cross section of a width equal to the width of the trough and of a length equal to the length of the trough, then cutting the timber longitudinally into V-shaped trough members, stacking the trough members to season, and in overlapping relation to each other in the same manner as cut from the timbers, and securing the triangularly shaped end members therein.

4. The method of forming a feeding trough having a V-shaped body portion and triangularly shaped end members, which consists in first forming a timber rectangular in cross section of a width equal to the width of the trough and of a length equal to the length of the trough, then cutting the timber longitudinally into V-shaped trough members, then removing the prism shaped member which results therefrom, then cutting the said prism shaped members transversely to form triangularly shaped end members, and then securing the end members in position.

Des Moines, Iowa, June 4, 1925.
